(57) **CLAIM**

The ornamental design for an inner pot for electrical rice cooker, as shown and described.

DESCRIPTION

FIG. 1 is a perspective view of an inner pot for electrical rice cooker showing our new design;

FIG. 2 is a front view thereof, opposite rear view being mirror image thereof;

FIG. 3 is a left side view thereof, opposite right side view being mirror image thereof;

FIG. 4 is a top plan view thereof;

FIG. 5 is a bottom view thereof; and,

FIG. 6 is a cross sectional view along the 6-6 line in FIG. 4.

1 Claim, 6 Drawing Sheets
